UNITED STATES PATENT OFFICE.

LEWIS T. HOUGHTON, OF WORCESTER, MASSACHUSETTS.

THREAD-GUIDE SUPPORT FOR SPINNING OR TWISTING MACHINES.

SPECIFICATION forming part of Letters Patent No. 677,988, dated July 9, 1901.

Application filed December 10, 1900. Serial No. 39,278. (No model.)

To all whom it may concern:

Be it known that I, LEWIS T. HOUGHTON, a citizen of the United States, residing at Worcester, in the county of Worcester and 5 State of Massachusetts, have invented a new and useful Thread-Guide Support for Spinning or Twisting Machinery, of which the following is a specification.

This invention relates to an improved construction for supporting the thread-guides of a spinning or twisting machine; and the object of this invention is to provide a lighter, stronger, more durable, and simpler support for such thread-guides than has heretofore 15 been used.

The thread-guide support forming the subject-matter of this invention is preferably stamped out of sheet metal and is designed to form an efficient cover for preventing loose 20 ends of thread or other matter from falling down, so as to become snarled with the driving-bands of the spindles, which will also have a smooth uninterrupted surface, which may be readily wiped, so as to prevent dirt 25 or dust from accumulating thereon.

To accomplish these ends, this invention consists of the parts and combinations of parts, as hereinafter described, and more particularly pointed out in the claims at the end 30 of this specification.

In the accompanying drawings, Figure 1 is a perspective view illustrating the application of a thread-guide constructed according to this invention to the frame of a spinning 35 or twisting machine. Fig. 2 is a transverse sectional view of the same. Fig. 3 is a detail perspective view of a thread-guide and means for clamping the same in place on the under side of the finger-head, and Fig. 4 is a 40 similar view illustrating a modified form of construction.

In the ordinary forms of spinning and twisting machines which are now placed upon the market a number of different constructions 45 have been devised for supporting the thread-guides.

In the older forms of spinning or twisting machines wooden finger-heads are employed, into which the thread-guides are directly 50 threaded or driven. In some of the latter forms of spinning and twisting machines me-

tallic constructions have been employed for supporting the thread-guides; but all of such constructions with which I am familiar are comparatively complicated and expensive and 55 in practical use are liable to become broken and deranged.

The especial object of my present invention is therefore to provide a support for the thread-guides of a spinning or twisting machine which will consist of the least possible 60 number of pieces and the parts of which are preferably stamped up out of sheet metal, so that the same will form a very strong substantial construction which may be readily 65 applied to the ordinary forms of spinning or twisting machines.

Referring to the accompanying drawings and in detail, A designates a portion of the side bar or framework of any of the ordinary 70 spinning or twisting machines, and secured to the framework A is a thread-guide support constructed according to this invention.

The thread-guide support as herein illustrated preferably comprises a finger-head 75 board and a number of finger-heads connected thereto by hinged joints, formed by parts which are integral with the finger-head board and finger-heads, respectively. The finger-head board 10 preferably consists of a com- 80 paratively long sheet-metal body portion having integral turned-down end flanges 12 and a rear flange 13. At one or more places along its rear edge the finger-head board 10 is provided with integral rolled or turned up por- 85 tions 14, which coöperate with a plate or butt 15 to form a hinge for connecting the finger-head board to the frame A. The finger-head board may, if desired, be formed of one continuous piece extending the entire length of the 90 machine, although in practice it is preferred to make the same in several separate lengths, which may be left independent or may be connected at the ends by screws, as illustrated in Fig. 2. Each of the finger-heads 11, which 95 are supported by the finger-head board, consists of a sheet-metal body portion having end flanges 27. The finger-head 11 is provided at its rear edge with integral turned or 100 rolled up sections 16, which are arranged to intermesh with turned or rolled up sections 17, formed integrally with the finger-head

board 10 to constitute the hinge-joint which connects said parts. The side flanges 27 of the finger-head 11 are arranged to extend back under the finger-head board 10 to form stops 5 for holding the finger-head in position when the same is turned down, as shown.

Any desired form of clamping mechanism may be used for clamping a thread-guide to the under side of the finger-head, although in 10 practice I prefer to employ a clamping mechanism which will permit a swinging and in-and-out adjustment of the thread-guide and which will leave the upper surface of the finger-head substantially uninterrupted.

15 As shown in Figs. 1 and 3, a thread-guide 20 may be adjustably clamped to the under side of the finger-head by means of a screw 18, which is threaded into a grooved clamp or holder 19. In some cases instead of employing this form of clamping mechanism I 20 may employ a U-shaped clamping-bolt 21 for engaging the shank of the thread-guide, which may be held in place by a nut 22, as illustrated in Fig. 4.

25 In a thread-guide support as thus constructed it will be seen that the finger-head board and finger-head are directly hinged together—that is to say, the sections forming the hinge-joint between these parts are formed 30 integrally therewith—and although I prefer to form this hinge-joint by integral intermeshing turned or rolled up sections on said parts other means may be provided for forming such direct hinge-joint.

35 I am aware that other changes may be made in the construction of my thread-guide for spinning or twisting machines, and I do not wish, therefore, to be limited to the construc-

tion which I have herein shown and described; but

40 What I do claim, and desire to secure by Letters Patent of the United States, is—

1. In a support for a thread-guide of a spinning or twisting machine, the combination of a sheet-metal strip or finger-head board, and 45 a finger-head having top and side flanges stamped from a single piece of sheet metal, and having integral sections at its rear edge bent or turned to form a socket for receiving the hinge-pin which connects the finger-head 50 to the finger-head board, the side flanges of the finger-head forming stops for holding the finger-head substantially horizontal when the same is in its turned-down position, substantially as described.

2. In a support for a thread-guide of a spinning or twisting machine, the combination of a sheet-metal strip or finger-head board, and a sheet-metal finger-head having the top and side flanges stamped from a single piece of 60 sheet metal, and having integral sections at its rear edge bent and rolled up to form a socket for receiving the hinge-pin which connects the finger-head to the finger-head board, and constructed so that the side flanges extend 65 back beyond the hinge-pin socket so as to form stops for supporting the finger-head, substantially as described.

55 In testimony whereof I have hereunto set my hand in the presence of two subscribing 70 witnesses.

LEWIS T. HOUGHTON.
